CLAIM

The ornamental design for a pocket for apparel, as shown and described.

DESCRIPTION

The sole FIGURE is a front view of an ornamental design for a pocket for apparel.

The dash-dash-dash broken lines in the FIGURE represent stitching and form a part of the claimed design. The dash-dot-dash broken lines in the FIGURE depict a boundary line and form no part of the claimed design. The contrast in shading represents a contrast in appearance only and does not represent any particular color, material, texture, or finish. The small black rectangles represent stitching and form a part of the claimed design.
